UNITED STATES PATENT OFFICE.

WILLIAM R. BURROWS, OF NEWARK, NEW JERSEY, ASSIGNOR TO GENERAL ELECTRIC COMPANY, A CORPORATION OF NEW YORK.

VAPOR ELECTRIC APPARATUS.

No. 853,678.

Specification of Letters Patent.

Patented May 14, 1907.

Application filed July 7, 1905. Serial No. 268,707.

To all whom it may concern:

Be it known that I, WILLIAM R. BURROWS, a citizen of the United States, residing at Newark, county of Essex, State of New Jersey, have invented certain new and useful Improvements in Vapor Electric Apparatus, of which the following is a specification.

This invention relates to an improved form of electrode suitable for use as anode in electric apparatus, such as mercury vapor lamps and rectifiers. The anodes of such apparatus should preferably be small in bulk and should at the same time present a considerable surface. I find that if electrodes are made of solid bodies of carbon or graphite it is difficult to draw out the occluded gases from the interior of the electrodes when the rectifier chamber is exhausted during manufacture and there is therefore a likelihood that these gases will be given up during the normal operation of the lamp or rectifier and thus lower the vacuum in the evacuated tube.

It is the object of this invention to provide an anode so shaped as to overcome the difficulties enumerated above, and so arranged as to properly protect the leading-in conductor from possible deterioration by the direct action of the mercury arc.

Figure 1 shows a rectifier of ordinary form provided with my improved anodes; Fig. 2 is a perspective view of an anode; and Fig. 3 is a sectional view of an anode and anode tube showing the arrangement of the various parts.

The rectifier 1 comprises an evacuated chamber of glass or other suitable material carrying at its lower end a tubular extension 2 filled with mercury to serve as cathode for the rectifier. It is also provided at the sides with tubular extensions 3 and 4 in which anodes 5 and 6 of artificial graphite are mounted. Anode 6 is mounted on a single platinum lead-wire 7, sealed in the wall of the anode tube. The inner surface of the glass tube is separated from the carbon anode by a lava bushing 8 which incloses the inner end of the platinum wire 7 and protects it from possible destruction by the mercury arc and furthermore serves to separate the glass surface from contact with the hot carbon anode 6.

Fig. 2 shows the details of my improved

form of anode and the modification there shown is provided with two lead wires 9 and 10 to increase the current carrying capacity of the anode connection, and to provide a firm mechanical support for the anode. The anode has a general tubular outline with wedge shaped grooves extending longitudinally thereof, thus leaving a central rib 11 of small diameter and a plurality of radially projecting webs 12. I may hollow out the central rib 11 by drilling a hole longitudinally therethrough up to a point near the ends of the leading-in wires but not far enough to uncover the ends of the wires and expose them to the destructive action of the arc. Such a construction has the advantage of presenting a large superficial area available for carrying an arc, but at the same time bringing all of the electrode material so near the surface that the removal of any gas is readily effected during the exhaustion of the lamp or rectifier.

Fig. 3 shows the method of mounting the anode in a rectifier tube, though it is to be understood that other means of support may be used if desired. The glass walls of the tube 13 are bent inward to form a second tube 14 through which the lead-wires are introduced and to the inner closed end 15 of which they are securely sealed. These lead wires 9 and 10 may be screw threaded or otherwise secured to the anode 6 and carry lava bushings 16 and 17 to separate the glass from the anode and to protect the lead-wires from the direct action of the arc. A suitable brass cap 18 may be cemented to the end of the glass tube 13 and soldered to the lead wires to afford a ready means of connection to an external circuit.

What I claim as new and desire to secure by Letters Patent of the United States, is:

1. An anode for vapor electric apparatus having a grooved exterior to provide a large superficial area and to facilitate the removal of gas from the interior.

2. An anode for vapor electric apparatus having a hollow center and a grooved exterior to provide a large superficial area and to facilitate the removal of gas from the interior.

3. A graphite anode for vapor electric apparatus having a hollow center and a grooved surface.

4. The combination with an evacuated

chamber, of an electrode therein having a hollow center and a longitudinally grooved exterior.

5. The combination with an evacuated chamber, of a lead-wire sealed in the wall thereof, and an electrode mounted on said lead-wire, said electrode completely inclosing the end of said lead-wire and provided with grooves to increase its superficial area.

10. 6. The combination with an evacuated chamber, of a lead-wire sealed in the wall thereof, and an electrode mounted on said lead-wire, said electrode having a hollow center and having certain portions cut away to increase its superficial area and to facilitate

15 the removal of occluded gases.

7. The combination with an evacuated

chamber, of a lead-wire in the wall thereof, and an electrode mounted on said lead-wire, said electrode having a plurality of radial 20 webs.

8. The combination with an evacuated chamber, of a lead-wire in the wall thereof, and an electrode mounted on said lead-wire and completely covering the end thereof, 25 said electrode having a plurality of radial webs.

In witness whereof I have hereunto set my hand this 5th day of July, 1905.

WILLIAM R. BURROWS.
